CLAIM

The ornamental design for an oral-motor chew tool, substantially as shown and described.

DESCRIPTION

FIG. 1 is a top, front, left perspective view of a first embodiment of an oral-motor chew tool, showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front side elevation view thereof;

FIG. 7 is a rear elevation view thereof;

FIG. 8 is a top, front, left perspective view of a second embodiment of an oral-motor chew tool, showing our new design;

FIG. 9 is a top plan view thereof;

FIG. 10 is a bottom plan view thereof;

FIG. 11 is a right side elevation view thereof;

FIG. 12 is a left side elevation view thereof;

FIG. 13 is a front side elevation view thereof; and,

FIG. 14 is a rear elevation view thereof.

1 Claim, 10 Drawing Sheets(56)
